UNITED STATES PATENT OFFICE.

FRANK M. BIXBY, OF DETROIT, MICHIGAN.

DESIGN FOR A BASE FOR HOLDBACKS.

SPECIFICATION forming part of **Design No. 25,008**, dated December 24, 1895.

Application filed June 8, 1895. Serial No. 552,173. Term of patent 3½ years.

To all whom it may concern:

Be it known that I, FRANK M. BIXBY, a citizen of the United States, residing at Detroit, in the county of Wayne, State of Michigan, 5 have invented and produced a new and original Design for a Base-Plate for Holdbacks, of which the following is a specification, reference being had to the accompanying drawing.

This invention relates to a new and original design for base-plates for holdbacks; and it consists of the peculiar formation illustrated in the accompanying drawing, in which a perspective view of my design is shown.

The leading feature of my design consists 15 of an angle-base A, whose opposite end por-

tions stand in separate planes, giving a bent form to said base, and which is provided with a raised central portion B, which slopes gradually toward one end of said base.

Having thus fully described my invention, 20 what I claim is—

The design for a base plate for hold backs, substantially as herein shown and described.

In testimony whereof I affix my signature in presence of two witnesses.

FRANK M. BIXBY.
